Primary Examiner — Cynthia Underwood(74) *Attorney, Agent, or Firm* — Rader, Fishman & Grauer PLLC(57) **CLAIM**

The ornamental design for a video camera, as shown and described.

DESCRIPTION

FIG. 1 is a perspective view of a video camera showing my new design; and,

FIG. 2 is a front elevational view thereof.

Portions in broken lines are for illustrative purposes only and form no part of the claimed design.

1 Claim, 2 Drawing Sheets(56)
